MACHINE FOR INSERTING CONTACTS INTO PANEL BOARDS

Charles Michael Lovendusky, Enola, Pa., assignor to
AMP Incorporated, Harrisburg, Pa.

Filed Aug. 24, 1964, Ser. No. 81,430

Term of patent 14 years

(Cl. D55—1)

FIGURE 1 is a perspective view of a machine for inserting contacts into panel boards, showing my new design;

FIGURE 2 is a right side view thereof;

FIGURE 3 is a left side view thereof;

FIGURE 4 is a front elevational view thereof;

FIGURE 5 is a top plan view thereof; and

FIGURE 6 is a rear elevational view thereof.

I claim:

The ornamental design for a machine for inserting contacts into panel boards, substantially as shown and described.
